DROP COUPLER FOR LOCOMOTIVES

Harry A. Hoke, Altoona, Pa., assignor to The Pennsylvania Railroad Company, Philadelphia, Pa., a corporation of Pennsylvania

Application December 5, 1938, Serial No. 243,945

16 Claims. (Cl. 213—4)

This invention has reference in its broader aspect to rolling stock coupling means of the type arranged for movement into or out of active position.

More specifically the present improvements relate to coupler means applicable to the front end of railroad locomotives and including a pivotally supported member capable of swinging out of the way, when not in use, and of being so retained by releasable means for gravitation to active position.

The primary object of the present improvements is to provide a drop coupler of the indicated character in which the keeper component is located above the center line of said coupler and forwardly relative to its fulcrum axis.

Another object is the provision of a drop coupler wherein the keeper passes through the coupler in both the active and inactive positions of the latter.

A further object has reference to provisions for effecting adjustment of the pivot on which the coupler swings up-and-down, as well as corresponding regulation of the position of the keeper.

A still further object is the provision of a drop coupler for locomotives which is comparatively simple in construction, rugged in character, effective in use, and easily manipulated.

Other objects and ancillary advantages of this invention will more fully appear from the following disclosure, considered in conjunction with the accompanying sheets of drawings which illustrate a preferred embodiment of said invention, while the concluding claims concisely express the features of novelty over prior art.

In the drawings:

Fig. I is a side elevation of a locomotive pilot structure including the improved drop coupler, of this invention, in active position.

Fig. II is a front elevation of the same as viewed from the left-hand of Fig. I, with parts broken out or in section.

Fig. III is a sectional plan on the line and looking in the direction of the arrows III—III of Figs. I and II.

Fig. IV is a vertical section on the plane IV—IV of Figs. II and III.

Fig. V is a corresponding view to the preceding, with the drop coupler in the inactive position.

Fig. VI is a fragmentary section on the plane VI—VI of Fig. IV.

Fig. VII is a transverse section on the plane VII—VII of Fig. IV.

Fig. VIII is a fragmentary section similar to Fig. VI, but showing the drop coupler and its

pivot supporting means, as well as the keeper, in raised position.

Fig. IX is a fragmentary sectional view corresponding somewhat to Fig. V, but showing the drop coupler and keeper in raised position.

Fig. X is a detail section on the plane X—X of Fig. II.

Fig. XI is a similar section, showing the drop coupler and keeper elevated.

Fig. XII is a perspective view of one of the keeper adjusting elements; and,

Fig. XIII is a perspective view of the drop coupler pivot supporting block.

In all the views, corresponding parts are designated by like characters of reference.

Referring more in detail to the drawings, the pilot structure of a railroad locomotive is comprehensively designated 1, the same being made of cast material having a cavity 2 with opposed apertured bosses 3, 4, and a pilot portion 5, including a central front opening 6 and flanking openings 7, the purposes whereof will be later on explained.

In accordance with this invention, each apertured boss 3, 4 is provided with a rectangular orifice 8, in which is removably-retained a correspondingly-sectioned block 9, best shown in Fig. XIII, having an eccentrically located bore 10 affording journal bearing for the drop-coupler pivot 11, said pivot being transversely held in place by appropriate means such as a head 12 thereon at one end, and a wedge pin 13 at the other end.

The drop coupler 14 of this invention comprises a head or claw 15 with a short shank or tongue 16, freely engaged between the forwardly-directed flanges 11, 17' of the hollow counterbalance 18, as by means of a headed pin 19 passed through registerable holes 20, 21, respectively, in the tongue 16 and flange portions 17, 17'; said pin being retained against displacement by a cotter 22. Thus it will be apparent that the drop-coupler 14 is movable up-and-down as a unit, on the pivot 11, while the claw 15 is laterally swingable to either hand on the pin 19, and in this latter connection the coupler tongue 16 is grooved at 23 so as to clear the drop-coupler pivot 11. It is to be particularly noted at this juncture that the drop-coupler 14 of this invention, by the means described, is directly connected by the pivot 11 to the locomotive front frame casting or pilot structure 1; also, that the axial centers of the pivot 11 and pin 19 are brought into close juxtaposition for compactness in construction.

The counterbalance 18 embodies a transverse pocket or recess 24, for loading with lead in accordance with known practice, and the projecting side walls 25 connected by the forwardly-directed flanges 17, 17' hereinbefore referred to. In addition the counterbalance 18 is provided with spaced enlargements or cheeks 26 having rectangular openings 27 therethrough, as well as a radially-related (in respect to the drop-coupler pivot 11) transverse hollow-portion 28, the bore 29 of the latter being similar in cross section to the openings 27. Each of the openings 27, as well as the bore 29 of the portion 28, is provided with bearing pads 30, 31; respectively for support of a key 32 and the counterbalance 18 when the coupler 14 is in the active position. This key 32 is fitted at one end with a draw handle 33 and at the other end has a pivoted knuckle-keeper 34, said key 32 being also engageable through 20 registerable rectangular apertures 35 in bracket portions 36 of the pilot structure 1.

Each bracket aperture 35 is of larger proportions than the cross-section of the key 32, for reception of an angle-section right-and-left hand reversible members 37, one only being shown in detail in Fig. XII, and each having a hole 38 through one of its flanges for axial registration with vertically-spaced and correspondingly screw-threaded holes 39, 40 in the front walls of the bracket portions 36, and a projecting or extension lug "e" for reducing the unsupported length of the key 32 and thereby lessening the stress thereat. Engageable in the holes 39, 40 are screw-studs 41 having their inner ends slightly reduced for engagement in a suitable groove 42 extending lengthwise of the key 32, and whereby said key may be guided and secured against unwarranted withdrawal by tightening-up of the studs 41 against lock washers 43 in an obvious manner. Conveniently, although not essentially, the key 32 may have the angular edges beveled at 44, for coaction with positioning ribs 45 on the members 37 as hereafter amplified; and the bearing blocks 9 may also have their longitudinal edges similarly beveled at 46 for coaction with complementary corner fillets 47 in the bearing orifices 3 and 4.

When it is desirable to raise the coupler 14 higher than the standard position shown by Figs. I-VII and X to that of Figs. VIII, IX and XI, in the event of differential elevation of the coupled means, the bearing blocks 9 are inverted or turned through an angle of one-hundred-eighty degrees so that the pivot 11 is raised, say one inch for instance. For similar reasons, the studs 41 are retracted from the lower holes 40 and the angle-sections 37 are inverted or positionally transposed, so that the plain flanges 37' thereof become disposed below, instead of above, the key 32; whereupon the studs 41 are inserted in the upper holes 39 and tightened up. Corresponding adjustment will also be made in the locking-releasing mechanism, comprehensively designated 48, by substituting a different length of actuator component 49. Inasmuch as the locking-releasing mechanism 48 forms a part of the invention disclosed in the application for a patent, filed September 8, 1937, under Serial No. 162,870, by Warren R. Elsey, reference may be had thereto for purposes of clarity, and more particularly to the equivalent components designated 45-55, inclusive.

From the foregoing it will be understood that when the drop-coupler 14 is in the normal or horizontal position best understood from Figs. I-IV, 75 that it will be prevented from vibrating up-and-

down by the key 32 engaging cross-wise of the pilot structure 1, through the bearing brackets 36 of the latter and the cheeks 26 of the counterbalance 18 above the fulcrum axis of the latter; and that it will be so retained by the locking-releasing mechanism 48. At the same time it will be well understood that the coupler claw 15 is free to swing laterally within limits, determined by stop-projections 50 at the front opening 6 of the pilot structure 1, as when the locomotive is rounding curves in the track rails. It is also to be particularly noted that by locating the key 32 above the center line of the coupler 14 and in advance of its pivot 11, and by providing the counterbalance 18 with back stops 51 for near engagement with the transverse wall 52 of the pilot structure, the several movably associated parts of the coupler are substantially prevented from any oscillatory movement. Still further, it will be clearly apparent that, when the drop-coupler 14 is not needed, the key 32 can be withdrawn and the locking-releasing mechanism 48 freed, whereupon said coupler will move or gravitate downwards until the claw 15 and counterbalance 18 approach the position of Fig. V with the former substantially within the confines of the pilot 5 and contacting the pilot structure at 53 and the counterbalance 18 swung up into the upper frontal part of the cavity 2. In this position it will be seen that upon reinsertion of the key 32 through the bracket apertures 35 and counterbalance transverse bore 29, the drop-coupler 14 will be firmly retained in out-of-use position and effectively restrained against vibration. Obviously, similar procedure will be adopted when the drop-coupler 14 is elevated as hereinbefore set forth, accordingly repetitive explanation is dispensed with.

The foregoing description is directed particularly to the illustrated construction of drop-coupler, but it is to be understood the privilege is reserved of resorting to all reasonable mechanical changes of which said drop-coupler is susceptible, and that the herein disclosed invention is defined and limited only by the terms of the following 45 claims and the condition of prior art.

Having thus described my invention, I claim:

1. In combination with the end structure of rolling stock, a pivotal drop coupler comprising a counterbalance with a claw swingable relative thereto, keeper means engageable through the counterbalance for holding the coupler in active position and restraining it against vibration when inactive, said means being located above and outwardly of the coupler pivotal axis, and reversible bearing members coacting with the coupler pivot and keeper means for changing the operating plane of the coupler.

2. The combination of claim 1 wherein the rolling stock end structure includes transversely spaced openings above and outwardly beyond the coupler pivotal axis, the counterbalance is provided with angularly-related complementary openings each of which is individually registerable with the first mentioned openings as desired, and the keeper means is in the form of a retractile bar for insertion through said openings to maintain the coupler in the active or inactive position.

3. The combination of claim 1 wherein the reversible means comprise invertible bearings for the drop coupler pivot, and invertible angle-section keeper-bearing members for coaction with the keeper means to jointly effect elevation of the coupler above its normal operating plane within corresponding limits.

4. Coupler means for railroad vehicles including a pilot structure comprising a pivotal drop coupler including a counterbalance with a claw relatively-swingable in respect thereto, a keeper engageable through the counterbalance and pilot structure for holding the coupler in active position and restraining it against vibration when inactive, said keeper being located above and outwardly of the coupler pivot axis, and reversible means coactive with the keeper and coupler pivot bearings for varying the operating plane of the coupler. 5
5. Coupler means for railroad vehicles including a pilot structure comprising a pivotal drop coupler including a counterbalance with a claw relatively-swingable in respect thereto, a keeper coactive with the pilot structure and the counterbalance for holding the coupler in active position and restraining it against vibration when inactive, said keeper being located above and outwardly in advance of the coupler pivot axis, and reversible bearing members coactive with the coupler pivot and keeper to raise the coupler higher than its normal operating position when necessary and to correspondingly elevate the 10 keeper. 20
6. The combination of claim 5 wherein the reversible members coactive with the coupler pivot and keeper comprise blocks having eccentrically-located journals for the coupler pivot, and angle-section keeper bearing members adapted by inversion to change the active plane of the keeper. 30
7. The combination of claim 5 wherein the pilot structure is provided with transversely spaced openings above and outwardly beyond the pivot axis of the coupler, the counterbalance has angularly-related openings each of which is movable into registration with the pilot structure transversely spaced openings, and the keeper is in the form of a bar for passage through said openings to sustain the coupler in differential active and 35 inactive positions. 40
8. In combination with a railroad locomotive pilot having a forward opening, a horizontally-pivoted and counterbalanced coupler, a claw laterally-movable relative to the counterbalance, a keeper coactive with the counterbalance and pilot for sustaining said coupler in active position and restraining it against vibration when inactive, said keeper being located above and outwardly in advance of the coupler pivot, and reversible bearing members cooperative with said keeper and the coupler pivot to elevate the plane of operation of the coupler. 45
9. In combination with a railroad locomotive pilot having a forward opening, a horizontally-pivoted coupler including a claw laterally-movable relative thereto, a keeper for sustaining said coupler in active position and restraining it against vibration when inactive, said keeper being located above and outwardly in advance of the coupler pivot, and reversible bearing members coactive with the coupler pivot and keeper to raise the coupler operating plane above normal when desirable and to correspondingly elevate the active 50 position of the keeper. 60
10. The combination of claim 5 wherein the reversible members respectively comprise bearing blocks having eccentric journals for the coupler pivot, and angle-section keeper bearing members for coaction with the keeper in differential positions. 65
11. The combination with a railroad locomotive pilot having a forward opening and flanking rectangular openings, a counterbalanced pivotal drop coupler including a laterally-swingable claw, bearing members in said rectangular openings affording different horizontal support for the coupler pivot, a retractile keeper engageable through the counterbalance for sustaining the coupler in active position and restraining it against vibration when inactive, said keeper being located above and outwardly in advance of the coupler pivot, and reversible members serviceable to raise the plane of operation of the retractile keeper in conformity with that of the coupler pivot. 70
12. The combination of claim 11 wherein the bearing members affording horizontal support for the coupler pivot consist of rectangular blocks each having an eccentrically located journal aperture therethrough, and said blocks have the diagonally-related corners lengthwise beveled for coaction with complementary fillets in the pilot rectangular openings. 15
13. The combination of claim 8 wherein the locomotive pilot has side openings transversely spaced above and outwardly of the pivot axis of the coupler; the counterbalance has angularly-related pairs of corresponding openings, either pair of which are individually registrable with the pilot openings; and the keeper is in the form of a bar for passage through the pilot side openings and the selected angularly-related counterbalance openings to sustain the coupler in differential active positions, and also to restrain said coupler against vibratory movement when inactive. 25
14. The combination of claim 11 wherein the keeper is in the form of a rectangular section bar for passage through a relatively larger bore in the coupler counterbalance, and opposed transverse rectangular openings in the pilot structure above and outwardly of the coupler pivot axis; and an invertible angle-section element is engaged in the respective pilot rectangular openings for holding the keeper bar in a normal position, as well as supporting said bar in a relatively 30 raised position. 40
15. The combination of claim 11 wherein the keeper is in the form of a rectangular section bar for passage through transverse rectangular openings in the pilot structure above and outwardly in advance of the coupler pivot axis, reversible angle-section bearing-members are inserted in said pilot openings to normally position or raise the active plane of the keeper respectively, and means securing the angle-section 45 bearing members in either position aforesaid. 50
16. The combination of claim 11 wherein the keeper is in the form of a rectangular section bar for passage through transverse rectangular openings in the pilot structure above and outwardly in advance of the coupler pivot axis; reversible angle-section bearing members are inserted in said openings to normally position or raise the active plane of the keeper respectively; and means consisting of screw-studs passing through vertically spaced threaded holes in the outer wall of the rectangular openings, with their ends adapted for coaction in a longitudinal groove of the keeper bar to secure the bearing members in either position as aforesaid. 60
